X-RAY TUBE

Filed March 1, 1922

INVENTOR
MONTFORD MORRISON

BY
J. Gilbert
ATTORNEY

UNITED STATES PATENT OFFICE.

MONTFORD MORRISON, OF NEW YORK, N. Y.

X-RAY TUBE.

Application filed March 1, 1922. Serial No. 540,141.

My invention relates to high tension electrical devices and more particularly it relates to certain improvements in apparatus for the generation of Roentgen or X-rays. 5

An object of the invention herein described is the provision of an X-ray tube capable of withstanding higher potentials. 10

Another object of the present invention is the provision of an X-ray device which 15 will afford greater safety to a patient exposed to the action of the same.

Other objects will be inferred from a reading of the following specification.

As the X-ray art advances it is found 15 desirable to construct increasingly more powerful X-ray generating units. One way of generating more powerful X-rays is by the application of higher voltages to the terminals of an X-ray device. In attempting, however, to operate X-ray tubes at increasingly higher voltages a point has been reached at which troubles have arisen to prohibit the use of voltages as high as is found desirable. One of these troubles has 25 been the corona phenomena occurring at the terminals of the electrodes.

The occurrence of corona, as known, is brought about when the electrostatic flux density in the air exceeds a certain value. 30 It is also known that the flux density for a given potential difference is greater the less the radius of curvature of the conductor. It will therefore be appreciated that by making the terminals of the electrodes in 35 an X-ray tube of such configuration that they will have large radii of curvature, corona effects will be diminished. In lieu, therefore, of electrode terminals having a small radius of curvature, it is proposed, 40 according to this invention to so construct the terminals that they shall have no points of protuberances or small radii but shall be formed to have comparatively large radii of curvature.

The formation of corona is objectionable 45 for the reason that there is a leakage of electricity from the conductors which the corona surrounds, which means that power is lost in this way. The effects of corona, however, 50 are more objectionable from another standpoint than that of the power loss, for the reason that in the regions where the corona appears the air is electrically broken down and ionized so that it becomes a conductor

of electricity, whereby a disruptive discharge 55 or spark is enabled to jump from one electrode to the other. The sparking or flash-over thus occurring of course diminishes, and hence limits, the penetrability of the X-rays and is therefore to be avoided. In 60 addition to the foregoing, other reasons may be cited why corona should be eliminated, such, for example, as the prevention of the formation of nitric acid and the consequent corrosion of the conductors on which the 65 corona forms.

The provision of electric terminals having large radii of curvature as proposed by this invention is especially valuable in X-ray tube constructions wherein it is desired to 70 remove the electrodes as remotely as possible from the patient subject to the action of the X-ray tube. A construction in which the electrodes are thus remotely removed is very desirable since in the past, accidents of 75 a serious and even fatal nature have resulted from X-ray tubes having a construction easily permitting personal contact with both electrodes. The usual form of commercial tube heretofore in use has consisted 80 of a spherical bulb having oppositely extending arms through which the electrodes pass. Such construction usually places the axis of the electrodes in a plane parallel to the body of a patient. According to the 85 present invention, however, the electrodes are directed away from a patient as remotely as practicable so as to avoid the danger of contact with the terminals which are charged to a high potential. This construction 90 has another advantage to which attention 95 will be hereinafter directed.

The accompanying drawing shows a side elevation of my improved tube embodying 95 illustrations of the features of my invention.

Referring to the drawing, a spherical glass bulb 1 encloses a cathode 2 and an anode 3 which respectively pass longitudinally through, and are sealed to, diverging cylindrical arms 4 and 5. The cathode 2, as shown in this instance, consists partially of a refractory material 6 wound into a helix and adapted to be heated electrically to incandescence through its leading-in wires 7 and 8. The anode 3 may consist of a target 10 having a face 11 and a conductor 12 leading to the target from the exterior of the bulb. Observing the position of the face of

the target, from which X-rays emanate, it will be noted that the electrodes are positioned so as to be remote from the objective of the X-rays, a feature of this invention which provides a safer X-ray tube.

At the upper extremities 14 and 15 of the arms 4 and 5 respectively, preferably at the points where the cathode and the anode emerge from these arms, terminals 16 and 10 17 are attached to the cathode 2 and the anode 3 respectively. The terminals 16 and 15 17 are, in this instance, shown as spheres having comparatively large radii of curvature, although, as previously stated, their configuration for the purpose of this invention may take other forms, provided the radii of curvature are comparatively large. As previously set forth, the provision of terminals of the kind described are effective 20 in preventing corona and in obviating flash-over between the terminals and they are especially valuable in a construction in which the electrodes are so positioned as to be relatively far removed from the objective of 25 the X-rays.

The novel positioning of the electrodes according to this invention, in addition to affording greater personal safety, affords an advantage in the manufacture of the target 30 of the tube. It is well known that the common form of X-ray target is necessarily beveled to properly direct the rays. In a tube of the present invention, however, a target which need not be beveled may be 35 used and an advantage is thus gained in the manufacture of the tubes.

While I have herein described one embodiment of my invention it is to be understood that many modifications may be made 40 therein but that these modifications are intended to be embraced in this invention as hereinafter claimed.

What is claimed is:

1. An X-ray tube comprising an evacuated envelope consisting of a main chamber provided with auxiliary extensions therefrom of substantially equal length, with approximately 45 90° therebetween, electrodes extending approximately along the axes of the extensions, converging toward each other and each provided with an external, substantially spherical, terminal of large size, for avoiding corona effects therebetween.

2. An X-ray device comprising an evacuated envelope formed as a main substantially spherical chamber with two substantially cylindrical extensions therefrom of substantially equal length, subtending an angle of approximately 90° therebetween, a cathode in one of said extensions and an anode in the other, converging toward each other and each provided with an external terminal with all its exterior surface having large radii of curvature for the purpose of avoiding corona effects therebetween, when high 65 voltage is applied to the device.

3. An X-ray tube comprising an envelope, electrodes disposed within said envelope and having terminals extending outside of said envelope, said terminals being of such shape 70 and form as to reduce corona effects.

4. An X-ray tube comprising an envelope, a plurality of electrodes disposed within said envelope and having terminal portions extending beyond the exterior surface of said envelope, said terminal portions having such a large radii of curvature as to substantially 75 prevent corona effects when high voltage is applied to said tube.

In testimony whereof, I have hereunto subscribed my name this 27th day of February 80 1922.

MONTFORD MORRISON.
